UNITED STATES PATENT OFFICE.

JOHN L. CHURCH, OF OAKLAND, CALIFORNIA.

DICE-GAME DEVICE.

1,353,380.

Specification of Letters Patent. Patented Sept. 21, 1920.

Application filed October 20, 1919. Serial No. 331,760.

To all whom it may concern:

Be it known that I, JOHN L. CHURCH, a citizen of the United States, residing at Oakland, in the county of Alameda and State of California, have invented certain new and useful Improvements in Dice-Game Devices; and I do hereby declare the following to be a full, clear, and exact description of the invention, such as will enable others skilled in the art to which it appertains to make and use the same.

The present invention relates to a dice game device, and has for its object the provision of such a device for tumbling or "shaking" dice by simply pressing a button, so that the dice are shaken within a case, to avoid the customary throwing of the dice by hand and the necessity of picking them up.

A further object is the provision of such a device having a dice tray mounted for vertical movement, and novel means to be operated by a push button for imparting a sharp upward movement to the tray for shaking or tumbling the dice thereon.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a longitudinal vertical section taken on the line 1—1 Fig. 2.

Fig. 2 is a bottom plan view.

Fig. 3 is a transverse vertical section taken on the line 3—3 of Fig. 2.

Fig. 4 is an enlarged sectional detail of the pivoted trip of the operating lever.

The device embodies a suitable base 1 having a rim 2 to seat on a table, counter or other support, and a bushing 3 is fitted in the base near the center thereof, and has a spindle 4 slidable vertically therein. A tray 5 is secured on the upper end of said spindle for supporting the dice, and is located within a case or hood 6 of glass or other transparent material, which is seated on the base to retain the dice on the tray. A nut 7 is threaded on the lower end of the spindle or stem 4 to seat against the lower end of the bushing 3 for limiting the upward movement of the tray.

As a means for raising the tray with a

sudden movement or jolt for shaking the dice, a lever 8 is disposed below the base in a longitudinal position, and is pivoted at one end, to a bearing 9 secured to and depending from the base. A cushion 10 is secured to the lower surface of the base 1 for the contact of the lever 8 thereby to cushion it when it is raised by means of the coiled expansion spring 14. This spring 14 is disposed within a tubular pocket 11 having its lower end closed, and said spring is confined between said lower end of the pocket and the lever 8 which extends through opposite vertical slots 12 in the wall of the pocket 11. The upper end of said pocket has ears 13 extending at an angle at the opposite sides of the slots 12, and secured by means of screws or otherwise to the lower surface of the base 1. This pocket 11 thus serves as a guide for the lever 8 so that it will swing in a vertical plane, and the spring raises said lever, thereby normally elevating the tray.

The operating means includes a vertical bushing 15 secured within the base and extending below same, and a plunger 16 slidable in said bushing and extending upwardly above the base, with a button 17 secured on the upper end of said plunger. A coiled wire expansion spring 18 surrounds said plunger and is confined between the push button 17 and a washer 19 bearing on the base, whereby to normally raise said plunger. The lower end of the plunger has a finger 20 extending at an angle through a longitudinal slot 21 in the bushing to engage a pivoted trip 22 carried by the free end of the lever 8. This trip 22 has a bifurcated portion 23 fitting astride the end of the lever and pivoted by means of the pin or rivet 24, permitting said trip to swing upwardly, but limiting its downward movement. A wire spring 25 is coiled around the end portion of the pivot pin 24, and engages the lever 8 and trip 22 to normally swing said trip downwardly to a position to be engaged by the finger 20. The plunger 16 moves downwardly in a vertical direction, while the trip 22 swings in an arc diverging away from the axis of the plunger 16, so that the finger 20 in depressing the trip 22 with the lever 8, will result in said trip and lever being released suddenly when the plunger moves downwardly a certain distance. The depression of the push button 17 is thus used for operating the device.

In operation, the push button 17 is de-

pressed, whereby the finger 20 in contacting with the trip 22 will swing the lever 8 downwardly, thereby compressing the spring 14 and permitting the dice tray 5 to gravitate with the lower end of the spindle or stem 4 seating on the lever 8. When the plunger 16 has moved downwardly a certain distance, the trip 22 in moving with the lever 8 in an arc will be released, so that the 10 spring will swing the lever upwardly with a sharp or sudden movement, thereby raising the spindle or stem 4 and dice tray. This will raise the tray with a jolt, and when the nut or member 7 strikes the lower 15 end of the bushing 3, the upward movement of the tray is stopped suddenly, causing the dice to be thrown upwardly from the tray. This will "shake" or tumble the dice. When the push button is released, the spring 20 18 will return it to raised position for the next operation, and the finger 20 in passing the trip 22, will swing said trip upwardly and the spring 25 will return said trip to a position to be engaged by said finger, when 25 the plunger is again lowered. This permits the finger 20 to pass the trip in the return of the plunger to normal position, but said trip can not swing downwardly on its pivot when the plunger is lowered thereby compelling 30 the lever 8 to swing downwardly. This device permits the dice to be shaken or tumbled quickly without throwing them by hand and gathering them up as usual.

Having thus described the invention, what 35 is claimed as new is:—

1. A dice game device comprising a vertically movable member, a dice tray movable vertically with said member, spring means for raising said member, and a plunger for depressing said member, said plunger and member having co-operating means includ- 40

ing a finger carried by one of them and a spring-return pivoted trip carried by the other for the contact of the finger in depressing said member and permitting the 45 finger to pass when the plunger is raised.

2. A dice game device comprising a base, a lever pivoted to the base, spring means for raising the lever, a stem slidable in the base and supported by said lever, a dice tray 50 mounted on said stem, and manually operated means for depressing said lever and releasing it during the depression movement of said manually-operated means.

3. A dice game device, comprising a base, 55 a lever pivoted to said base underneath same, spring means for raising said lever, a stem slidable in the base and supported by said lever, a dice tray mounted on said stem, and a plunger slidable in the base, said 60 plunger and lever having means for depressing the lever with said plunger, and releasing said lever.

4. A dice game device comprising a base, a lever underneath the base pivoted at one 65 end, spring means for raising the lever, a stem slidable in the base and supported by the lever, a dice tray on the stem, a plunger slidable in the base having a push button, spring means for raising the plunger, a trip 70 pivoted to the other end of the lever to swing upwardly, spring means for swinging said trip downwardly, and a finger carried by the plunger to contact with said trip for depressing the lever. 75

In testimony whereof I have signed my name to this specification in the presence of two subscribing witnesses.

JOHN L. CHURCH.
